UNITED STATES PATENT OFFICE.

EUGENE G. MERGENTHALER, OF BALTIMORE, MARYLAND; SAFE DEPOSIT AND TRUST COMPANY OF BALTIMORE AND HERMAN C. MERGENTHALER, EXECUTORS OF SAID EUGENE G. MERGENTHALER, DECEASED, ASSIGNEES OF ONE-HALF TO SAFE DEPOSIT AND TRUST COMPANY OF BALTIMORE, TRUSTEE, AND ONE-HALF TO HERMAN C. MERGENTHALER.

TYPE AND TYPE-DISTRIBUTING MECHANISM.

1,359,518.

Specification of Letters Patent. Patented Nov. 23, 1920.

Application filed September 25, 1918, Serial No. 255,690. Renewed April 13, 1920. Serial No. 373,537.

To all whom it may concern:

Be it known that I, EUGENE G. MERGENTHALER, a citizen of the United States, residing at Baltimore city, State of Maryland, have invented certain new and useful Improvements in Type and Type-Distributing Mechanism, fully described and represented in the following specification and the accompanying drawings, forming a part of the same.

This invention relates to improvements in distributing mechanism for linotype machines and particularly to secondary or font distributing mechanisms therefor, that is to say, mechanisms designed, after the primary distribution of type or matrices according to character, to make a further distribution thereof according to the case, size or other variations in the characters.

It also relates to improvements in matrices designed for use with such mechanisms.

For convenience the improvements of the present invention are illustrated and described herein in connection with the well known Mergenthaler linotype machines, but it is to be understood that the present improvements are applicable to other machines.

In the accompanying drawings—

Figure 1 is an end elevation of a distributing mechanism embodying the improvements of the present invention in their preferred form.

Fig. 2 is a horizontal section (partly broken away) on the line 2 of Fig. 1.

Fig. 3 is a vertical section, on an enlarged scale, on the line 3 of Fig. 2.

Fig. 4 is a horizontal section on the line 4 of Fig. 3.

Fig. 5 is a vertical section thereof on the line 5 of Fig. 3.

Fig. 6 is a section on the line 6 of Fig. 1.

Fig. 7 is a perspective view of one of the matrices.

Fig. 8 is a view similar to Fig. 1, illustrating a modification hereinafter described.

Fig. 9 is a view similar to Fig. 3, illustrating the same modification; and

Fig. 10 is a vertical section on the line 10 of Fig. 9.

In these drawings the present invention is shown, and it will be hereinafter particu-

larly described, as a secondary distributing mechanism in connection with the well known linotype distributing or primary distributing mechanism, but it is to be understood that, except as otherwise indicated in some of the claims, the invention is not so limited.

Referring particularly to Figs. 1 to 7, the primary distributing mechanism there shown comprises the usual longitudinally ribbed stationary distributing bar 1 depending, at its ends, from blocks 2 suitably supported in the side frames (not shown) of the machine, and a set of feed screws 3, 4, 5, journaled in brackets 6, 7, depending from blocks 2, and which engage and feed the matrices along the bar 1. The matrices are toothed for engagement with the ribs on bar 1 and their teeth and these ribs are so permuted with relation to each other that as the matrices reach certain positions lengthwise of the bar, determined by the character they bear, they are released by and drop from the bar. In single font machines they pass thence to their respective channels in a magazine. In multiple magazine machines there are two distributing operations, namely, a primary one according to font or character, and a secondary one, according to character or font, the matrices so distributed passing into their proper channels in their respective magazines.

The primary distributing mechanism shown in Figs. 1 to 6 is like that in common use in linotype machines. The drive therefore is, however, different from that usually employed, being such as to secure a step-by-step movement, instead of a continuous movement, of the matrices along the distributing bar 1. For this purpose there are provided a driving pulley 10 (driven from any suitable source of power) fixed to a shaft 11 journaled in lateral extensions 12 of brackets 6, a segmental gear 13 fixed to shaft 11, a broad faced intermediate 14, gears 15, 16 meshing therewith and fixed to distributor screws 3, 5, and gear 17 fixed to distributor screw 4.

From this construction it results that during the first half revolution of pulley 10 and its shaft 11 (in the direction of the arrow Fig. 1) segmental gear 13 will rotate inter-

mediate 14, and, through it, gears 15, 16, 17, and their screws 3, 4, 5, thus feeding the matrices along bar 1, and that during the second half revolution of pulley 10 and its shaft 11, the segmental gear 13 being out of mesh with intermediate 14, there will be no rotation of gears 15, 16, 17 and therefore no movement of the matrices, the movement of the matrices along bar 1 being thus a step-by-step movement.

During these movements the matrices are distributed into groups, according to character, and the type of these groups are then redistributed according to case or font.

The parts of this step-by-step mechanism are so arranged and timed relatively to each other, that on each "step" or turning movement of the distributing screws 3, 4, 5, the string of matrices suspended from distributing bar 1 will be moved longitudinally of the bar a distance equal to the thickness of a matrix, so that on each such turning movement no more than one matrix bearing the same character will be distributed and dropped from bar 1. This is for the purpose of providing for the accurate feeding or movement of the matrices as thus primarily distributed to the font or secondary distributing mechanism 18 hereinafter described.

To avoid overthrow or continued rotation of gears 15, 16, 17, and therefore of distributing screws 3, 4, 5, when segmental gear 13 runs out of mesh with intermediate 14, a positive stop is provided for then engaging said intermediate and locking it against movement. This consists of a latch or pawl 20 pivoted in an ear 21 projecting from one of the bracket extensions 12 and the nose of which pawl is adapted to engage a pin 22 projecting laterally from intermediate 14. The movement of this pawl into and out of engagement with the pin 22, as the segmental gear 13 runs out of and into mesh with intermediate 14, is effected by a cam 23 fixed to shaft 11, and engaging the tail of the pawl. This cam is so arranged relatively to the toothed portion of segmental gear 13 that as the latter meshes with intermediate 14 this cam will engage the tail of the pawl and move its nose out of engagement with the pin 22 (as shown in Fig. 1) while as segmental gear 13 passes out of mesh with intermediate 14, cam 23 will be disengaged from the tail of pawl 20, the nose of which will then drop into the path of movement of and engage said pin and thus lock intermediate 14 against further rotation, in which position it will continue until cam 23, at the end of the half revolution which segmental gear 13 is then making, again engages the tail of pawl 20 and moves the latter out of engagement with pin 22.

Beneath and extending longitudinally of from bar 1, and to position the pushers 32

distributer bar 1 there is provided a table 25, suitably supported in the frame of the machine, for receiving the matrices dropped from said bar, and between this table and said bar there is also provided a matrix 70 guiding frame 26, open at top and bottom and provided with front and rear plates 27, 28, and, between the latter, with transverse vertical partitions 29 suitably distanced apart to provide matrix guiding 75 channels 30 for the matrices as they drop from bar 1. The frame 26 is suitably supported in the frame of the machine with its channels 30 in proper position with relation to bar 1 for the matrices which they are 80 respectively designed to receive. These partitions and channels 29, 30, extend downwardly toward table 25 so as to properly support the matrices in an upright position thereon, as shown in Fig. 4.

On one side of the table 25 there is provided a matrix feeding or moving mechanism and on the other a font-distributing mechanism to which are fed or moved by it the groups of distributed matrices as they 90 drop from bar 1.

The feeding or moving mechanism consists of a plurality of reciprocating pushers 32 resting upon table 25, one for each of the channels 30. These pushers are connected with a rod 33 provided at its opposite ends with blocks 34 adapted to be moved back and forth in guideways 35. Rod 33 is connected by a link 36 with one end of a bell crank lever 37 pivoted in one of the 100 bracket extensions 12 and the opposite end of which is provided with a bowl 38 entering a cam groove 39 in the face of a disk 40 fixed to shaft 11, as best shown in Fig. 1.

As the parts are shown in Fig. 1, the 105 pushers 32 are in their forward position, that is to say, projected across table 25 through channels 30, from which they have moved any matrices present therein into the font or secondary distributing mechanism 110 18. At this time, as well as during such forward movement of the pushers 32, the distributing screws 3, 4, 5 are stationary and there is, therefore, no movement along distributing bar 1 of the string of matrices suspended therefrom. As segmental gear 13 rotates from this position (in the direction of the arrow Fig. 1) it meshes with, and for a half revolution continues in mesh with, intermediate 14, thus rotating screws 3, 4, 125 5 and moving the string of matrices along bar 1 a distance equal to the thickness of a matrix, matrices released from bar 1 then dropping through channels 30 onto table 25. In the meantime, and during this half revolution of segmental gear 13, bell crank 37 is rocked outwardly by cam 39 so as to withdraw the pushers 32 from channels 30, to make way for any matrices that may drop 120 from bar 1, and to position the pushers 32

for moving such matrices from these channels into the font or secondary distributing mechanism. The bell crank 37 and pushers 32 remain in this position until this half revolution of segmental gear 13 is about completed, when the cam 39 will move them in the opposite direction so that the pushers will move the matrices then deposited in channels into the font or secondary distributing mechanism. In other words, during one half a revolution of segmental gear 13 the matrices are moved along bar 1 a distance equal to the thickness of a matrix and the pushers 32 are moved rearwardly or out of the channels 30, while during the next half revolution of gear 13 there is no movement of the matrices along bar 1 and the pushers 32 are moved forward or projected across table 25 and through the channels 30 to move therefrom and into the font or secondary distributing mechanism such matrices as may have dropped therein; and so on. The movement of pushers 32 is such that they will move the matrices from channels 30 and also move them in the font distributor a distance equal to the width of a matrix.

The font or secondary distributing mechanism 18 which is suitably supported in the machine, comprises side plates 45, 46, and, between the latter, rails 47 providing matrix guides equal in number to the several groups of matrices from bar 1. These rails 47 are designed to receive the matrices from table 25 and for this purpose they register with the partitions 29 and are suitably spaced apart to provide channels 47' registering with the channels 30, while the upper edges of said rails occupy a position in line, horizontally, with the upper ends of the matrices as they rest on said table.

This font or redistributing mechanism 18 has been designed particularly with the present-day linotype machine in mind and it will be observed that it can readily be applied to such machines. The rail arrangement in it has also been devised with the present-day linotype matrices in mind so that such matrices may be used therewith with but little change in the structure, the only change required being the cutting away of a small amount of the metal horizontally and vertically on opposite sides of the matrix near its upper ends to provide channels 48 the upper walls of which consist of a plurality of shoulders 49, there being preferably a pair of such shoulders on each side of the matrix. The lower walls 50 of channels 48, inside the bases of the shoulders, constitute guides for the matrices, to prevent tilting thereof, while moving along the rails 47, which are designed to enter these channels as the matrices are delivered from table 25, while the shoulders 49, co-acting with corresponding type-releasing

openings 51 in rails 47, determine the distribution of the matrices into their respective fonts.

The shoulders 49 are of different thicknesses or different distances apart, or both, in different matrices of the same character or group, as indicated in Fig. 3; in other words, the shoulders are differently disposed relatively to each other on the several matrices of a group.

The shoulders 49 do not extend beyond but are undercut or flush with the sides of the type so that the thickness of any of the matrices is not increased or decreased. Therefore, present-day matrices may readily be altered to provide the channels 48 and shoulders, or new matrices may be made with them, without the necessity of any changes in the construction of or methods of position in linotype machines now in use.

The openings 51 in the rails 47 are arranged in sets longitudinally of the rails corresponding in number of sets and in relative widths and separation to the shoulders 49 on the matrices.

From this it results that as the matrices are moved along the rails 47 the latter will retain them (suspended by their shoulders 49) until they reach their respective matrix or type releasing openings 51 when the shoulders 49 will be released from the rails 47 and the matrices so released will drop therefrom into guiding tubes 52 leading to their respective magazines. The walls 50 of the channels 48 in the matrices, with the shoulders 49, prevent tilting and consequent jamming of the matrices on the rails 47. These walls 50 need not be continuous, as shown, although it is most convenient to so make them.

In the construction shown in Figs. 8 to 10, the movement of the matrices along the bar 1 is continuous, instead of step-by-step as in Figs. 1 to 6, and the movement of the matrices from table 25 into the font distributor 18 is accomplished by belts 55, 56. The gears 15, 16, 17 of feed screws 3, 4, 5, are driven by a gear 57, which is in turn driven from some suitable source of power (not shown). Belt 55, which is mounted on pulleys 58, 59, is driven by gear 16 through an intermediate 60 engaging a gear 61 fixed to the shaft of pulley 58, and performs the function of moving the matrices from table 25 into the secondary distributor 18. Belt 56, which is mounted on pulleys 62, 63, is driven by gear 17 through an intermediate 64 meshing with a gear 65 fixed to the shaft of pulley 62, and performs the function of feeding the matrices through the secondary distributor 18 as they are delivered thereto by the belt 55.

For convenience I have used the word "matrix" herein, but it is to be understood that I include herein any type whether in-

taglio or cameo, and for this reason I use the word "type" in the following claims.

What I claim is:

1. The combination with a plurality of type provided on their sides with undercut distributing shoulders differently arranged on the several type and beyond the bases of said shoulders with guides to prevent tilting of the type during distribution, of a distributing member coacting with said guides and shoulders and provided with type-releasing openings conforming to the latter.

2. The combination with a plurality of type each provided on both of its sides with undercut distributing shoulders differently arranged on the several type and beyond the bases of said shoulders with guides to prevent tilting of the type during distribution, of a pair of distributing members arranged to embrace the type and coacting with said guides and shoulders and provided with type-releasing openings conforming to the latter.

3. The combination with a plurality of type provided on their sides with undercut distributing shoulders differently arranged on the several type and beyond the bases of said shoulders with guides to prevent tilting of the type during distribution, of a distributing member coacting with said guides and shoulders and provided with type-releasing openings conforming to the latter, and mechanism for moving the type along the distributing member.

4. The combination with a plurality of type each provided on both of its sides with undercut distributing shoulders differently arranged on the several type and beyond the bases of said shoulders with guides to prevent tilting of the type during distribution, of a pair of distributing members arranged to embrace the type and coacting with said guides and shoulders and provided with type-releasing openings conforming to the latter, and mechanism for moving the type along the distributing members.

5. The combination with a set of type having suitable selecting means for their primary distribution into groups and provided on their sides with undercut distributing shoulders differently arranged on the several type of each group and beyond the bases of said shoulders with guides to prevent tilting of the type during distribution, of primary distributing mechanism coacting with the first-named selecting means to distribute the type into groups, and a distributing member coacting with said guides and shoulders and provided with type-releasing openings conforming to the latter.

6. The combination with a set of type having suitable selecting means for their primary distribution into groups and provided on both of its sides with undercut

distributing shoulders differently arranged 65 on the several type of each group and beyond the bases of said shoulders with guides to prevent tilting of the type during distribution, of primary distributing mechanism coacting 70 with the first-named selecting means to distribute the type into groups, and a pair of distributing members for each group of type arranged to embrace the type and coacting with said guides and shoulders and provided with type-releasing openings 75 conforming to the latter.

7. The combination with a set of type having suitable selecting means for their primary distribution into groups and provided 80 on their sides with undercut distributing shoulders differently arranged on the several type of each group and beyond the bases of said shoulders with guides to prevent tilting of the type during distribution, of primary distributing mechanism coacting 85 with the first-named selecting means to distribute the type into groups, a distributing member coacting with said guides and shoulders and provided with type-releasing openings 90 conforming to the latter, and mechanism for moving the type from the primary distributing mechanism to and along said distributing guides.

8. The combination with a set of type having suitable selecting means for their 95 primary distribution into groups and provided on both of its sides with undercut distributing shoulders differently arranged on the several type of each group and beyond the bases of said shoulders with guides 100 to prevent tilting of the type during distribution, of primary distributing mechanism coacting with the first-named selecting means to distribute the type into groups, a pair of distributing members for each group 105 of type arranged to embrace the type and coacting with said guides and shoulders and provided with type-releasing openings conforming to the latter, and mechanism for moving the type from the primary distributing mechanism to and along said distributing 110 guides.

9. A set of type provided with two sets of selecting devices for their primary and secondary distribution, one set comprising undercut shoulders on the sides of the type, and guides beyond the bases of said shoulders.

10. A set of type provided with two sets of selecting devices for their primary and 120 secondary distribution, one set comprising undercut shoulders on both sides of each type, and guides beyond the bases of said shoulders.

In testimony whereof I have hereunto set 125 my hand.

EUGENE G. MERGENTHALER.
